T. J. COPE.
SUPPORT FOR ELECTRIC CONDUCTORS.
APPLICATION FILED MAY 25, 1914.

Patented Feb. 23, 1915.

UNITED STATES PATENT OFFICE.

THOMAS J. COPE, OF PHILADELPHIA, PENNSYLVANIA.

SUPPORT FOR ELECTRIC CONDUCTORS.

1,129,553.

Specification of Letters Patent. Patented Feb. 23, 1915.

Application filed May 25, 1914. Serial No. 840,962.

To all whom it may concern:

Be it known that I, THOMAS J. COPE, a citizen of the United States, residing in the city and county of Philadelphia, State of Pennsylvania, have invented a new and useful Support for Electrical Conductors, of which the following is a specification.

My invention relates to an improvement in a support for electrical conductors as shown in the Letters Patent No. 647,945, granted to me, on the 24th day of April, 1900, and consists in so constructing the support that its elbow is adapted to be interlocked with the edge of the standard instead of with the body of the same, between the edges thereof, whereby said bracket may be more conveniently applied to and removed from said standard, and the latter may be formed of cast metal instead of more expensive wrought metal, as shown in said Letters Patent.

The invention is satisfactorily illustrated in the accompanying drawing, but the important instrumentalities thereof may be varied, and so it is to be understood that the invention is not limited to the specific details shown and described.

Figure 1 represents a perspective view of a support for electric conductors embodying my invention. Fig. 2 represents a partial plan view thereof, and partial horizontal section thereof on the line $x-x$ Fig. 1. Fig. 3 represents a side elevation of a portion opposite to that shown in Fig. 1. Fig. 4 represents an end elevation at a right angle to Fig. 1. Fig. 5 represents a side elevation of a modification. Fig. 6 represents a partial side elevation and partial vertical section on the line $y-y$ Fig. 4.

Similar numerals of reference indicate corresponding parts in the figures.

Referring to the drawings, 1 designates a standard or bar which is adapted to be secured in vertical direction to a desired place, the same having in its side edge the recesses 2 which are located thereon parallel, one below the other. 3 designates a bracket which is adapted to be supported on said bar 1, it having on its upper face the depression 4 or seats 4 on which electrical conductors may be placed and sustained. On what may be termed the inner end of the bracket is the leg 5, at the base of which on one side thereof is the outturned foot 6. On the upper end of said leg is the outturned neck 7, on whose outer end is the inturned elbow

8. On the vertical side of said neck above the leg, above the foot 6 is the shoulder 9 which extends in inclined direction from the top of the leg to about the place 10 when it 60 extends in perpendicular direction as at 11 to the bottom of the leg, the inner end of the bracket at the top of said inclined shoulder 9 having thereon the outturned limb 14 forming an angle with said shoulder, as 65 most plainly shown in Fig. 1, said shoulder being on the side of the leg to which the foot 6 is applied, and facing the elbow 8 so that a space exists between the latter and said elbow whereby the bracket may be raised 70 and lowered on the bracket to permit of the introduction into and connection of the bracket with said standard in a convenient manner, without liability of the bracket dropping from the standard, while the limb 75 14 fulcrums sidewise on the edge of the standard in turning and introducing said elbow 8 into the recess 2, the same being true of said limb in the withdrawal of said elbow from said recess, thus rendering said introduction and withdrawal easy of operation.

The operation is as follows:—The bracket is raised to an extent and presented to the standard so that the elbow 8 is in register with the side of the desired recess 2 that it is 80 to occupy. The inclined shoulder 9 of the bracket contacts with the adjacent edge of the standard, thus removing the foot 6 from the latter especially from said edge. The bracket is now manipulated to pass the 85 elbow into said recess when the inner or transverse limb of said elbow will occupy said recess, and the longitudinally or outer limb of the elbow will be on the side of the standard opposite to the neck 7. Then the 90 bracket is lowered, the transverse limb of the elbow turning on the wall of the recess 2, when the foot 6 overlaps the side of the standard, as does also the outer limb of the elbow, said elbow and foot projecting toward each other, and as is evident, occupying the same side of the standard, while the neck 5 occupies the opposite side of the standard. When the bracket is lowered to full extent, the perpendicular portion 11 of 100 the shoulder 9 abuts against the edge of the standard opposite to the recess 2, and so the bracket is sustained firmly in horizontal direction on the standard, while it is interlocked with the latter on opposite sides 105 thereof, and thus displacement of the bracket from the standard is prevented, un-

less it is desired to so displace or remove it, when it may be raised, the inclined shoulder which is set back from the adjacent edge of the standard, allowing the elevation of the bracket, when the latter may be manipulated laterally on said limb to withdraw the elbow 8 sidewise from the recess that it occupied, and remove the foot 6 from the side of the standard, when the bracket is entirely disconnected from the standard.

In some cases, it may be desired to have the inner limb of the elbow point upwardly as at 12, Fig. 5, instead of laterally in Figs. 1, 2, 3, and 4, when the elbow may be inserted in an opening 13 in the body of the standard, said opening being somewhat elliptical to permit said inner limb to be introduced into said opening, but the bracket is supported with the other members shown in said Figs. 1, 2, 3, and 4, while the standard has a recess 2 in the edge of its side, when it is desired to apply the elbow thereto as in said figures.

Having thus described my invention what I claim as new and desire to secure as Letters Patent, is:—

1. In a support of the character stated, a standard with recesses therein, and a bracket for coöperation therewith, said bracket having on its engaging end, a depending leg, an outturned foot on the base of the latter adapted to overlap said standard, an outturned neck on the upper end of said leg, an inturned elbow on said neck adapted to overlap said standard on the same side of said foot and opposing the same, an inclined

shoulder on said neck spaced from said elbow and facing the same, providing means for the introduction and connection of the bracket with said standard, and a laterally-extending limb on the inner end of said bracket at the top of said inclined shoulder, said laterally-extending limb, said inturned elbow, and said outturned-foot occupying their positions on the same side of the bracket.

2. In a support of the character stated, a standard with recesses therein, and a bracket for coöperation therewith, said bracket having on its engaging end a depending leg, an outturned foot on the base of the latter adapted to overlap said standard, an outturned neck on the upper end of said leg, an inturned elbow on said neck adapted to overlap said standard on the same side of said foot and opposing the same, an inclined shoulder on said neck spaced from said elbow and facing the same, providing means for the introduction and connection of the bracket with said standard, a portion of said shoulder extending from the lower terminal of the inclination thereof in a perpendicular direction to the bottom of the leg, and a limb extending laterally from the inner end of the bracket at the top of said inclined shoulder, said limb being on the same side of the bracket as said inturned-elbow and said outturned-foot.

THOMAS J. COPE.
